[57] CLAIM

The ornamental design for a “toy excavator”, as shown and
described.

DESCRIPTION

FIG. 1 is a top, front and right side perspective view of a toy
excavator according to my design;

FIG. 2 is a top plan view thereof;

FIG. 3 is a front elevational view thereof;

FIG. 4 is a right side elevational view thereof;

FIG. 5 is a rear elevational view thereof;

FIG. 6 is a left side elevational view thereof; and,

FIG. 7 is a bottom plan view thereof.

The shadows on the enclosed photographs cast in the
photographic process are disclaimed and do not form part of
the claimed design.
